(57) **CLAIM**

The ornamental design for a Smith bar catch, as shown and described.

DESCRIPTION

FIG. 1 is a right perspective view of a Smith bar catch, showing my new design;

FIG. 2 is a left perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 2;

FIG. 12 is a partial enlarged view of FIG. 2;

FIG. 13 is a partial enlarged view of FIG. 3;

FIG. 14 is a partial enlarged view of FIG. 3;

FIG. 15 is a partial enlarged view of FIG. 4;

FIG. 16 is a partial enlarged view of FIG. 4;

FIG. 17 is a partial enlarged view of FIG. 5;

FIG. 18 is a partial enlarged view of FIG. 5;

FIG. 19 is a partial enlarged view of FIG. 6;

FIG. 20 is a partial enlarged view of FIG. 6; and,

FIG. 21 is a right perspective view of the Smith bar catch, indicating the usage environment.

The broken lines in the figures are for the purposes of illustrating portions of the Smith bar catch, which form no part of the claimed design.

The dash-dot-dash lines are for annotating enlarged views, which form no part of the claim design.

The broken lines in FIG. 21 are directed to the usage environment, which form part of the claimed design.

1 Claim, 14 Drawing Sheets
